INVENTOR.

BY Erich J. Michaelis

ATTORNEY.

UNITED STATES PATENT OFFICE

WILLIAM H. THEEL, OF CHICAGO, ILLINOIS

TRAFFIC MARKER

Application filed November 24, 1930. Serial No. 497,767.

The invention relates to traffic markers and the object of the invention is to provide a traffic marker which can be inserted in the pavement of a street with the least expense, time, and work.

Another object of the invention is to provide a traffic marker in the shape of a plate or the like, having attached thereon or formed integrally therewith a stem provided with radially extending shoulders acting like barbed hooks and preventing the stem from slipping upwardly after it has been set or driven into the ground.

Another object of the invention is to provide a traffic marker having a stem thereon as indicated above and provided with longitudinal slots therein adapted to receive an expansion member, provided to cooperate with said stem and to be forced into the slotted stem, when the traffic marker is put in position, thereby expanding the different portions of the stem from each other and forcing the shoulder into the road bed.

Other objects of the invention not specifically mentioned will be easily ascertained and understood from the following description in connection with the accompanying drawings forming a part thereof. It is however to be understood, that the invention is not to be limited or restricted to the exact construction or formation shown in the drawings and described in the specification, but that said invention is only to be limited by the scope of the claim appended hereto. In the drawings, illustrating a preferred embodiment of the invention

Fig. 1 is a sectional view taken on line 1—1 of Fig. 2 and showing a traffic marker according to the present invention ready to be set in position on the road bed, and

Fig. 2 is a sectional view taken on line 2—2 of Fig. 1.

Fig. 3 is a detail view showing the lower ends of two oppositely located portions of the stem and especially the shoulders on the end of said portions.

The traffic marker as shown in the drawings consists of a plate 5 made from any suitable material and coated by a cover 6 of rubber or the like. On the plate 5, which is

shown as a circular disc, a stem 7 is provided extending downwardly from said disc. It is however to be understood, that the plate may be of any desirable and convenient outline and that a plurality of stems may be attached or formed on said plate without violating the spirit of the invention.

The lower portion of stem 7 is provided with a series of ratchet like shoulders 8 which are shaped so, that the shoulders will act like barbed hooks preventing an upward movement of the stem, after the same has been driven into the ground or into a road bed, formed of concrete or the like.

This lower part of the stem is divided into a plurality of longitudinal portions by one or more slots extending radially into said stem. On the lower end of each longitudinal portion 9 an inwardly extending shoulder 10 is formed for a purpose to be described later.

An expansion member 11 consists of a circular base 12, having a diameter which is preferably somewhat smaller than the diameter of the stem 7. On top of the base 12 a conical portion 13 is formed and extends upwardly and ends into a ball shaped part 14.

The stem is preferably made of a resilient metal, so that the longitudinal portions 9 may be spread from each other. The expansion member is preferably made from a hard metal.

In order to set the traffic marker a hole is drilled into the road bed having a somewhat bigger diameter, than the stem. The globular end 14 of the expansion member is forced into the stem between the longitudinal portions thereof. This is possible since the stem is made from a resilient metal. The shoulders 10 on said portion will engage the expansion member underneath the globular end, and will hold the said member attached to the stem. The whole marker is then placed in position, so that the base of the expansion member will rest on the bottom of the hole drilled into road bed, and that the stem will be located in said hole. The depth of the hole should be such, that the lower surface of the marker plate will be located somewhat above the road surface, when the base of the ex-

expansion member rests on the bottom of the hole. When then the marker plate is forced downwardly in any convenient and suitable manner, so as to rest on or to be embedded into the road surface the expansion member will be driven or forced into the stem thereby expanding the longitudinal portions 9 and forcing the ratchet teeth 8 into the ground or the material forming the road bed. The shape 10 of the teeth will then prevent any upward movement of the stem so, that through the engagement of the road bed by said teeth the traffic marker will be held firmly and securely in position.

15 Having described my invention and how the same is to be performed, I claim as new and desire to secure by Letters Patent:

In a device of the class described a stem having upwardly and radially extending 20 shoulders and consisting of a plurality of longitudinal portions, each portion having on its lower end an inwardly extending shoulder, and an expansion member having a conical body and a globular upper end adapted to be 25 forced between said longitudinal stem portions and to be engaged and held by the end shoulders on said portions.

In witness whereof I affix my signature.

WILLIAM H. THEEL.
